UNITED STATES PATENT OFFICE.

VICTOR R. KOONTZ, OF WAYNESBORO, PENNSYLVANIA, ASSIGNOR TO VICTOR TOOL COMPANY, OF WAYNESBORO, PENNSYLVANIA, A CORPORATION OF PENNSYLVANIA.

COLLAPSIBLE TAP.

1,353,048.

Specification of Letters Patent. Patented Sept. 14, 1920.

Application filed November 16, 1918. Serial No. 262,835.

To all whom it may concern:

Be it known that I, VICTOR R. KOONTZ, a citizen of the United States, residing at Waynesboro, Franklin county, and State of Pennsylvania, have invented and discovered certain new and useful Improvements in Collapsible Taps, of which the following is a specification.

My said invention relates to improvements in taps for cutting internal threads, and more particularly to collapsible taps of that class that are designed for cutting threads on the inside of pipes and the like.

The object of my said invention is to provide a tap of the character stated which, while having positive collapsible features, is comparatively simple in its construction, light, durable, and easy to operate, all of which will be hereinafter more fully described and claimed.

Referring to the accompanying drawings, which are made a part hereof and on which similar reference characters indicate similar parts:

Figure 1 is a longitudinal section through a tap constructed in accordance with my said invention;

Fig. 2, a view of the inner end thereof;

Fig. 3, a cross-section on the dotted line 30 3—3 in Fig. 1; and

Fig. 4, a view showing the outer end thereof.

In said drawings, like characters of reference indicate similar parts in the several views. The main body portion 10 of the device is cylindrical in form and provided with radial slots 11 in one end for the reception of chasers or cutters 12. Said chasers are provided with cutting teeth 13 on their outer edges and their inner edges 14 are beveled or tapered. Grooves 15 are cut in one side of each chaser and are parallel with the beveled edge 14. A plunger 17 is mounted in a central bore with which the several radial slots communicate. Said plunger is provided with a series of grooves 18 correspondingly beveled to the bevel portion 14 of the cutters and provided with fins 19 which fit snugly within the grooves 15. The plunger 17 is provided with a threaded opening 20 in which fits a threaded portion 21 of a size-adjusting screw 22 which is cylindrical in form and provided adjacent the portion 21 with a flange 23 for a pur-

pose to be explained later. The body portion 10 is provided adjacent the bore 16 with an internal flange 24 which separates the bore 16 from a similar bore 25 formed therein. A spring 26 is located within the bore 25 and one end bears against an adjustable nut 27 which is threaded on the end of the screw 22 while its opposite end bears against the flange 24. This spring is under tension to force the screw 22 together with the plunger 17 outwardly, which, through the action of the bevel portion of the plunger and chasers, withdraws the chasers. In order to hold the chasers in their operative position, I have provided a latch 28 which is pivoted on a pin 29 in a slot 30 cut in the body portion 10 and held in its locked position by means of a spring 31 embedded in sockets formed in the latch and in the lower side of the slot 30. A notch 44 is formed in the end of the latch 28 and co-operates with the flange 23 of the size adjusting screw 22 to hold the cutters out in operative position.

Threaded on the outside of the body portion 10, is a gage collar 32 which is split and provided with a locking screw 33 to securely bind it to prevent its displacement. This collar is to limit the distance to which the thread is to be cut.

The end of the body portion adjacent the cutters is closed by means of a member comprising a disk 34 secured thereby by screws 35. Projecting from this disk is a stem 36 supporting a head 37 which is cylindrical in form and used for the purpose of guiding the tool into the work to be threaded.

In order to lock the plunger in any particular position, a locking screw 38 is provided which has one end 39 threaded into one end of the size adjusting screw 22 and its opposite end projecting through the screw 22 and provided with a slot 40 for the reception of a screw driver. Both the size adjusting screw and the nut are provided with slots 41 and 42 respectively, for the reception of a wrench of suitable form.

The end of the body portion 10 is squared off as at 43 to receive the squared portion of a suitable handle (not shown).

In operation, the parts are set to cut the size and depth of work desired. The operation proceeds in the usual way. When the set-collar 32 limits the cutting, latch 28 is

released and spring 26 operates to collapse the die, when it may be withdrawn from the work, and reset, and the operation proceeded with as before.

5 Having thus fully described my said invention, what I claim as new and desire to secure by Letters Patent is:

1. A tap comprising a body portion, chasers radially mounted in the end of said body portion, a plunger coacting with said chasers, a second adjustable plunger coacting with the first mentioned plunger, a collar formed on said second plunger, a spring-pressed latch co-acting with said collar to hold said plunger at one end of its stroke, a nut secured at the opposite end of said second mentioned plunger, a flange formed on the inner side of the bore in said body portion, and a spring co-acting between said flange and said nut to retract the said plungers, substantially as set forth.

2. A collapsible tap comprising, a body having an axial bore, chasers radially movable in and beyond said body, a cam adapted to move said chasers, a plunger, variable connection between the plunger and cam, a spring adapted to act through the plunger and cam to contract the chasers, means to vary the tension of the spring and means to latch the spring against action.

3. A collapsible tap comprising, a body having an axial bore, chasers radially movable in and beyond said body, a cam adapted to move said chasers, a plunger, screw-threaded connection between the plunger and cam, a spring adapted to act through the plunger and cam to contract the chasers, means to vary the tension of the spring and means to latch the spring against action.

40 4. A collapsible tap comprising, a body having an axial bore, chasers radially movable in and beyond said body, a cam adapted to move said chasers, a plunger, variable

connection between the plunger and cam, means to lock the variable connection, a spring adapted to act through the plunger and cam to contract the chasers, means to vary the tension of the spring and means to latch the spring against action.

5. A collapsible tap comprising, a body having an axial bore, chasers radially movable in and beyond said body, a cam adapted to move said chasers, a plunger, screw-threaded connection between the plunger and cam, means to facilitate the rotation of the plunger to vary the combined length of plunger and cam, a spring adapted to act through the plunger and cam to contract the chasers, means to vary the tension of the spring and means to latch the spring against action.

6. A collapsible tap comprising, a body having an axial bore, chasers radially movable in and beyond said body, a cam adapted to move said chasers, a plunger, screw-threaded connection between the plunger and cam, a threaded bolt extending axially through the plunger and bearing against the cam, means to facilitate the rotation of the plunger to vary the combined length of plunger and cam, means to facilitate the rotation of the threaded bolt, a spring adapted to act through the plunger and cam to contract the chasers, means to vary the tension of the spring, means to facilitate the manipulation of the spring tensioning means, all of said facilitating means being juxtaposed to the end of the plunger and means to latch the spring against action.

In witness whereof, I have hereunto set my hand and seal at Waynesboro, Pennsylvania, this 6th day of November, A. D. nineteen hundred and eighteen.

VICTOR R. KOONTZ. [L. S.]
